Assistant Examiner — Nicole M. Leech

CLAIM

The ornamental design for an outdoor decoration, as shown and described.

DESCRIPTION

FIG. 1 is a perspective view of an outdoor decoration showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view thereof, showing the outdoor decoration in a state of use; and,

FIG. 9 is an enlarged view thereof, taken from portion 9 in FIG. 1.

The dot-dash broken lines of FIGS. 1 and 9 are included to show a partially enlarged view only and form no part of the claimed design.

1 Claim, 9 Drawing Sheets
